UNITED STATES PATENT OFFICE.

IRVINE M. NOBLE AND WALTER E. GOSSLING, OF INDIANAPOLIS, INDIANA, ASSIGNEES
TO THE PREST-O-LITE COMPANY, INC., OF INDIANAPOLIS, INDIANA, A CORPORATION
OF NEW YORK.

METHOD OF AND TOOL FOR SECURING CONNECTING PARTS OF BATTERY-PLATES.

1,302,699.

Specification of Letters Patent.

Patented May 6, 1918.

Application filed November 26, 1917, Serial No. 204,028. Renewed September 25, 1918. Serial No. 255,703.

To all whom it may concern:

Be it known that we, IRVINE M. NOBLE, a citizen of the United States, residing at Indianapolis, Marion county, and State of Indiana, and WALTER E. GOSSLING, a citizen of the United States, residing at Indianapolis, Marion county, and State of Indiana, have invented and discovered certain new and useful Improvements in Methods of and 10 Tools for Securing Connecting Parts of Battery-Plates, of which the following is a specification.

The object of our said invention is to provide a method and means for securing plate- 15 connector posts of storage batteries to the battery cover in an expeditious and inexpensive manner, the particular character of connection between said posts and cover being that illustrated in our application for Letters Patent No. 187,873, filed August 23, 20 1917. The present invention resides largely in the tool or implement employed.

Referring to the accompanying drawing which is made a part hereof and on which 25 similar reference characters indicate similar parts, Figure 1 is a view showing one corner of a battery cell in section with a plate-connector post secured in the cover as shown and described in our above mentioned application, and by the use of the tool, and 30 the process forming the subject matter of this application, the tool being shown in the position it occupies in the process, complete, and the joint between the part formed, 35 and

Fig. 2 a section through the body of the tool.

In said drawing, the portion marked A represents the battery cover; B the plate 40 connector post; C the plate-connector; D one of the battery plates; E the wooden separator separating the positive and the negative plates; F the body of the cell; G the battery box; and H the seal around the 45 outer edge of the battery cover, all of which parts may be of a well known or any approved construction.

The tool for forming the joint between the plate-connector post and the cover, consists of a body 10 having a tapered socket 11 in its lower end of a size and form corresponding to the size and form desired for the upper end of the post. Just above the inner end of said socket said body 10 is pro-

vided with annular perforations 12 and 13, 55 the perforation 12 extending to a point near the inner end of said socket, and the perforation 13 cutting into said perforation 12 from the other side of the body at a point a very short distance above its inner end. 60 A bracket 14 is attached to one side of said body adjacent to the outer end of the perforation 12 and a gas torch or burner 15 is mounted in said bracket with its nozzle or discharge end arranged to direct the flame 65 into perforation 12. The gas burner is connected with a mixing chamber 16, and a gas supply pipe 17 may lead from any source of supply, such as an acetylene gas tank, as will be readily understood. The body 10 is 70 provided with a stem 18 of appropriate dimensions, and a handle, or cross bar, or pin, 19 may be inserted in a transverse perforation near the upper end of said stem for the purpose of manipulation and handling of 75 the tool.

While we have shown a gas burner as a means for heating the tool, it will be understood, of course, that any means found appropriate may be employed for this purpose, 80 such as appropriate electrical means, if found more convenient.

In operation the parts are assembled by inserting the post B through the aperture in the battery cover A until the annular 85 flange 20 bears against the under face of said cover, when said post fits tightly in said aperture. Sealing material of common character may be provided in said aperture if found necessary or desirable.

The tool is then pressed down over the top of the post, it being designed to be of slightly less diameter than the normal diameter of the post at a point near the cover so that the lower end of the socket 11 impinges upon the surface of the post a short distance before the end of the tool reaches said cover. The body 10 being hot, causes the metal of the post to soften or fuse sufficiently so that a quantity of the metal will 100 be forced into each annular recess around the top edge of the aperture in the cover and form the annular flange 21, filling said recess, or form a flange overhanging the top edge of the aperture, according to whatever 105 type of joint is to be formed.

Because of the character of the metal of which the post is composed, and the high

temperature of the body 10, the tool can be crowded down upon the top of the post to form the joint described with very little effort, and the work be done with great rapidity. Its inner lower corner may be formed slightly rounded, as shown, and by turning the tool as it is forced down a neat and perfect joint is formed, and one proof against the leakage of the electrolyte.

10 Having thus described our said invention what we claim as new and desire to secure by Letters Patent, is:

1. The method of securing the connector post of battery plates to the battery cover which consists in inserting said post through an aperture in said cover then heating the part of the post above the cover to slightly fuse the metal and pressing the metal down around the edge of the opening in said cover, substantially as set forth.
2. A tool for use in securing the connector posts of battery plates to the cover of the battery cell comprising a body member having a socket adapted to fit over the top of said post and impinge against the surface

thereof at a point slightly above the cover, means for heating said member and means for pressing said member down on said post to force metal from its periphery down around the edge of the opening in said cover, substantially as set forth.

3. A tool for securing plate connector posts to the covers of battery cells comprising a member with a socket adapted to fit over the top of said post, means for heating said member, means for forcing said member downward on said post, the lower end of said socket at its inner edge being shaped to form a flange on said post around the top edge of the opening in said cover, substantially as set forth.

In witness whereof, we have hereunto set our hands and seals at Indianapolis, Indiana this 20th day of November, A. D., nineteen hundred and seventeen.
